[57] CLAIM

The ornamental design for an angel doll as shown and described.

DESCRIPTION

FIG. 1 is a front elevational view of the angel doll of the present invention;

FIG. 2 is a back elevational view of the angel doll of FIG. 1;
FIG. 3 is a left side elevational view of the angel doll of FIG. 1;

FIG. 4 is a right side elevational view of the angel doll FIG. 1;

FIG. 5 is a top plan view of the angel doll of FIG. 1; and,
FIG. 6 is a bottom plan view of the angel doll of FIG. 1.
The broken lines showing an audio playback device in FIG.
2 are for illustrative purposes only and do not form part of
the claimed design.
